(57) **CLAIM**

The ornamental design for an all-purpose multi-carrier label, as shown and described.

DESCRIPTION

FIG. 1 is a front elevational view of an allpurpose multi-carrier label showing my new design, with the broken line showing for illustrative purposes only and forming no part of the claimed design;

FIG. 2 is a front elevational view of a second embodiment thereof;

FIG. 3 is a front elevational view of a third embodiment thereof, wherein the backing ply carries a delivery confirmation label;

FIG. 4 is a rear elevational view of the above embodiments; and,

FIG. 5 is a rear elevational view of the above embodiments, wherein the label shows the carrier with intervally spaced horizontal perforations formed therein.

It should be understood that the labels for each of the embodiments are of no substantial thickness such that a side view is not required.
